Primary Examiner — Elizabeth J Oswecki(74) *Attorney, Agent, or Firm* — Law Office of Ken Dallara; Ken Dallara(57) **CLAIM**

The ornamental design for an embossed Easter style egg, as shown and described.

DESCRIPTION

FIG. 1 is a top, left side, isometric view of an embossed Easter style egg showing my new design;

FIG. 2 is a front elevation view thereof;

FIG. 3 is a right side elevation view thereof;

FIG. 4 is a bottom, right side, isometric view thereof;

FIG. 5 is a top, right side, isometric view thereof;

FIG. 6 is a top plan view thereof;

FIG. 7 is a bottom plan view thereof; and,

FIG. 8 is a left side elevation view thereof.

All surfaces not shown form no part of the claimed design.
